UNITED STATES PATENT OFFICE.

PHILLIPP J. RABB, OF FRANKFORT STATION, ILLINOIS.

POTATO-PLANTER.

SPECIFICATION forming part of Letters Patent No. 433,031, dated July 29, 1890.

Application filed April 25, 1890. Serial No. 349,474. (No model.)

To all whom it may concern:

Be it known that I, PHILLIPP J. RABB, a citizen of the United States of America, residing at Frankfort Station, in the county of Will 5 and State of Illinois, have invented certain new and useful Improvements in Potato-Planters, of which the following is a specification, reference being had therein to the accompanying drawings and the letters of reference thereon, forming a part of this specification, in which—

Figure 1 is a top plan view of the potato-planter. Fig. 2 is a vertical section through the center of the hopper and a side view of the bevel-gears underneath it for rotating the pocketed dropping-plate, looking toward the forward part of the machine. Fig. 3 is a perspective view of the pocketed dropping-plate and a portion of its shaft, and Fig. 4 is a side 20 elevation of the machine.

This invention relates to certain improvements in potato-planters, which improvements will be fully set forth in the following specification and claim.

Referring to the drawings, A represents the main frame of the machine, made of suitable timbers and provided with an axle P, a pair of traveling wheels J, and a tongue T, to which a team may be attached to propel the machine.

H. is a hopper for holding seed-potatoes, which hopper rests on and is secured to the upper rear sides of the two parallel beams E E, the forward ends of which beams are pivoted to the under side of the front cross-bar of the frame A, so that their rear ends with the hopper H may have vertical adjustment.

B is a rock-shaft journaled to the top of a cross-bar of the main frame immediately at 40 the rear of the hopper H. This rock-shaft has secured to it the lever L for rotating said shaft, which lever is provided on its side with the latch R for engaging the notched segment K, secured on said cross-beam, which latch has its rear end extended far enough so that it can be operated by the foot of the operator as he rides on seat D. The two ends of shaft

B are provided with arms S, that extend forward, one on either side of the hopper H, 45 and are connected at their outer ends with said hopper by means of the links S' S', hav-

ing their lower ends pivoted to the outer ends of the cross-beam Z, secured across the under rear side of the hopper. By means of such connection of the hopper with the rock-shaft 55 B the hopper may be elevated and lowered with the shoe G, which has the rear part secured to the under side of said hopper and its forward end pivoted to the under side of the forward cross-bar of the frame A. 6c

The latch R and notched segment K serve to regulate the height to which it may be desired to adjust the hopper, reference being had to the character of soil over which the machine is traveling.

a is a circular pocketed rotating dropping-disk, located centrally in the bottom of the floor F and in a corresponding circular recess in the removable floor F', located on the upper side of floor F. This disk a is larger in diameter at its bottom than at its top, and has an inclosing-band i, forming the outer walls of the pockets n. These pockets n are larger in area at the bottom than at the top, so that the seed will the more readily pass 75 through them.

r is a knife secured in the hopper-bottom in such manner as to overlie a pocket as it moves over an aperture in floor F that registers with the throat of the shoe G. The use 80 of said knife is to sever any large seed that may project above the plate and likely not drop through as its pocket comes in position to drop. A vertical shaft C passes down through the center of the disk a and floor F, and is stepped in the arm Y, secured to the bottom of said floor, and has secured on its lower end the bevel-gear m, which meshes with bevel-gear m'. The bevel-gear m' is secured on a short horizontal shaft that is boxed 90 at one end in said arm and at its opposite end in a box secured to the beam E on its under side, as shown in Fig. 2, so said bevel-gear can mesh with bevel-gear m, secured on the lower end of the said vertical shaft C. 95 Said horizontal shaft has also secured on it the sprocket-wheel S², over which passes the sprocket-chain e.

X is a toothed drive-wheel secured on shaft W', which is boxed at each end in the lower 100 ends of the arms V and V'. Said shaft W' has secured on it the sprocket-wheel S⁴, which

- connects with sprocket-wheel S^2 through the medium of the sprocket-chain e . A slot V'' in arm V furnishes means for adjusting said drive-wheel X vertically, so as to cause it to enter the ground any required depth. Said drive-wheel drives the dropping-disk a through the medium of said sprocket-chain and bevel-gear mechanism as the machine travels forward.
- 10 In operation the potatoes to be planted are placed in the hopper H and cover the dropping-disk a , and also fill the pockets n in said plate. Said disk a is intended to be of such thickness as to cause these pockets to be deep enough to receive enough seed to form a hill of potatoes. As the said disk revolves, these pockets pass successively over a throat through floor F , (shown in broken lines in Fig. 4,) leading to the throat in the rear 15 part of the shoe G , which is of the ordinary pattern. The knife r extends over said throat and covers a pocket as it is in position over said throat to drop, as shown in Fig. 1, and should seed fail to drop through into said 20 throat when in such position said knife will sever it, so that the portion in the pocket may drop down to the ground through said throat,

to be covered by ordinary scraper-boards Q , arranged in the rear of said shoe. It is intended to have these dropping-disks a interchangeable for others having different-sized pockets for different-sized seed, and for that reason the floor F' is removable and shaft C is square on the upper end and passes loosely through said plate, so that it may be readily 35 removed for said purpose.

The whole forms a very cheap, durable, and effective machine for the purpose specified.

Having thus described my invention, what I claim as new, and desire to secure by Letters 40 Patent, is as follows, to wit:

In the potato-planter shown and described, the combination of the adjustable beams E E , bearing a hopper H , provided with dropping-holes in its base, the adjustable arms V V' , toothed wheel X , sprocket-wheels S^2 S^4 , sprocket-chain e , bevel-gears m m' , rotating dropping-disk a , knife r , and the means for vertically adjusting said beams, substantially as and for the purpose set forth.

PHILLIPP J. RABB.
